UNITED STATES PATENT OFFICE.

CHARLES E. GODLEY, OF DETROIT, MICHIGAN, ASSIGNOR, BY MESNE ASSIGNMENTS,
TO EDMUND & JONES CORPORATION, OF NEW YORK, N. Y., A CORPORATION OF
NEW YORK.

BULB-SUPPORT FOR ELECTRIC LAMPS.

1,202,056.

Specification of Letters Patent.

Patented Oct. 24, 1916.

Application filed January 5, 1916. Serial No. 70,360.

To all whom it may concern:

Be it known that I, CHARLES E. GODLEY, a citizen of the United States, and a resident of Detroit, in the county of Wayne and 5 State of Michigan, have invented a new and Improved Bulb-Support for Electric Lamps, of which the following is a specification.

This invention relates to means for securely and non-revolubly mounting electric bulbs within lamp bodies, and its object is to provide a supporting device that will be simple, that may be easily removed from the lamp body, and that may be constructed 15 at low cost.

This invention consists in the combination of a sleeve connected to any desirable part of the lamp, in which sleeve the bulb-supporting coupling is mounted and which 20 sleeve has an opening in its wall, a coupling normally slidable within the sleeve and provided with a narrow longitudinal groove, and a spring formed of flat metal and embracing said sleeve and having an inturned 25 portion extending through the opening in the wall of the sleeve so as to engage the coupling and also having its end extending into the groove in said coupling.

In the accompanying drawing, Figure 1 30 is a central vertical section of a lamp provided with this improved bulb supporting device. Fig. 2 is a section on the line 2—2 of Fig. 1. Fig. 3 is a section through a reflector to which the bulb supporting sleeve 35 is connected, the construction of the sleeve being slightly modified so as to permit the bulb to be moved back and forth in order to focus it. Fig. 4 is a perspective view of a securing spring. Fig. 5 is a section of 40 the coupling shown in Fig. 3.

Similar reference characters refer to like parts throughout the several views.

In the lamp shown in Fig. 3, the reflector 1 has secured to it a sleeve 2 formed with an 45 opening 3. In this sleeve is normally slid- able and revoluble a coupling 4 having a conductor 5 attached to its outer end in any desired manner, and provided with the usual bayonet slot 6 to receive the pin 7 50 on the socket 8 of the bulb 9, and a recess 10, preferably in the form of a longitudinal groove 10. A spring 12 of flat metal has a body portion that tightly embraces the sleeve 2 for nearly one half of its circum- 55 ference, then an outwardly extending por-

tion 13 which permits a tool being inserted to remove the spring, then an inwardly extending portion 14 that extends through the opening 3, and finally an inturned end 15 that enters the recess 10.

The pressure of the portion 14 of the spring on the coupling 4 prevents this from moving endwise except under considerable stress, and while permitting the bulb 9 to be focused, holds it in any desired position. 60 The lip 15 extending into the recess 10, limits the endwise movements of the coupling and also prevents it from being turned, a very desirable characteristic when bulbs having silvered or sanded portions 65 are employed. But by simply removing the spring 12, the coupling is entirely freed and can be slipped out of the sleeve 2 in either direction.

The groove 10 may be of any desired 70 length, and in lamps such as shown in Fig. 1, need be no longer than the width of the spring. The coupling there shown is somewhat of the same general character as that shown in Fig. 3, and has a metal shell 16, 75 a body 17 of insulating material in which two metal sleeves 18 are mounted to receive wires that extend in through the cap 19 80 screwed onto the lower end of the body 17. A bulb 21 has a socket 22 extending into 85 the shell 16, and this socket has contacts 23 and 24 engaged by the contact rods 25 that are mounted in the metal sleeves 18 and pressed outward by the springs 26. Neither 90 of these couplings forms any part of the present invention.

The coupling 16 is mounted in the sleeve 27, secured to the lamp body 28, and is formed with a recess to receive the inturned end 15 of the spring 12, as shown in Fig. 2. 95

Where the metal parts of the lamp and its support are employed as one of the conductors for the current of the lamp, a single contact rod or pin 30 may be employed, as indicated in Fig. 5. The length of the 100 groove 10 and the length of the lip 15 determine the distance the lamp bulb can be moved, and where no movement is necessary or desirable, the length of the groove may be the length of the lip 15.

I claim:

1. In a bulb-support for electric lamps, the combination of a sleeve having an opening through its wall, a bulb-supporting coupling mounted in said sleeve and provided 110

with a longitudinal groove, and a spring mounted on the sleeve and extending into said opening to engage the coupling and having one end extending into said groove 5 to prevent the coupling from turning.

2. In a bulb-support for electric lamps, the combination of a sleeve having an opening through its wall, a bulb-supporting coupling mounted in said sleeve and having a 10 longitudinal groove in its surface, and a spring mounted on said sleeve and having one end extending through the opening in the sleeve into the groove in the coupling to prevent the coupling from turning in the 15 sleeve, said groove being of greater length than the width of the spring so as to permit longitudinal movement of the coupling in the sleeve.

3. In a bulb-support for electric lamps,

the combination of a cylindrical sleeve 20 mounted on the lamp and provided with an opening through its wall, a cylindrical coupling normally slidable and revolvable in said sleeve and provided with a longitudinal groove, and a spring mounted on the sleeve 25 and consisting of a curved portion embracing the sleeve, an inturned portion extending into said opening and engaging the coupling to hold it in position, and a lip on the end of the spring adjacent the inturned 30 portion and extending into said groove to prevent the coupling from turning in the sleeve and to limit its longitudinal movement.

In testimony whereof I sign this specification.

CHARLES E. GODLEY.
